DESIGN FOR A COMBINATION TOAST SERVER AND TOASTER COVER

Richard I. Felver, Mansfield, Ohio, assignor to Westinghouse Electric & Manufacturing Company, a corporation of Pennsylvania

Application July 31, 1942, Serial No. 107,772

Term of patent 14 years

To all whom it may concern:

Be it known that I, Richard I. Felver, a citizen of the United States and a resident of Mansfield, in the county of Richland and State of Ohio, have invented a new, original, and ornamental Design for a Combination Toast Server and Toaster Cover, of which the following is a specification, reference being had to the accompanying drawing, forming part thereof, in which:

Figure 1 is a perspective view, taken from the front and one side, of a combination toast server

and toaster cover, showing my design, the concealed side of the apparatus being like the side shown; and

Figure 2 is a perspective view of the combination toast server and toaster cover in its inverted or toast serving position.

I claim:

The ornamental design for a combination toast server and toaster cover, substantially as shown and described.

RICHARD I. FELVER.
